UNITED STATES PATENT OFFICE.

BERNARD II. BLANK, OF NEW YORK, N. Y., ASSIGNOR TO HAMMEL,
RIGLANDER & CO., OF SAME PLACE.

DESIGN FOR AN OPERA-GLASS HOLDER.

SPECIFICATION forming part of **Design No. 25,838, dated July 28, 1896.**

Application filed June 1, 1896. Serial No. 593,926. Term of patent 7 years.

To all whom it may concern:

Be it known that I, BERNARD II. BLANK, a citizen of the United States, residing in the city, county, and State of New York, have invented and produced a new and original Design for Opera-Glass Holders, of which the following is a specification.

The essential feature of my design resides in the configuration of the holder, substantially as shown in the accompanying drawings, in which—

Figure 1 is a front elevation, and Fig. 2 a side elevation.

The holder comprises a handle portion 1 and the enlargement 2, which latter is formed by the two parallel side portions 3, swelling outwardly from the union of the enlargement and handle, as at 4, and turning in again at 5 where they are extended forward parallel to the plane of the side pieces 5 to form extensions 6, the extensions being located at one side of the central longitudinal axis of the side pieces.

In side elevation the handle 1 is shown flaring toward the bottom and narrowing toward the point 4. The side pieces 3 are shown provided at one side with an inwardly-extending segmental recess 7 and on the other side with two recesses 8 and a segmental projection 9.

The extensions 6 are reduced in diameter and rounded, and their axis extends at an angle to the longitudinal axis of the holder proper.

Having described my design, I claim—
35
The design for an opera-glass holder, substantially as herein shown and described.

Signed in the city, county, and State of New York this 20th day of May, 1896.

BERNARD II. BLANK.
